UNITED STATES PATENT OFFICE.

EDWARD S. ROSENBLUTH, OF HARTFORD, CONNECTICUT.

DESIGN FOR A CORSET.

SPECIFICATION forming part of Design No. 18,031, dated January 24, 1888.

Application filed September 5, 1887. Serial No. 348,905. Term of patent 7 years.

To all whom it may concern:

Be it known that I, EDWARD S. ROSENBLUTH, of Hartford, in the county of Hartford and State of Connecticut, have invented 5 a new and original Design for Corsets, of which the following is a full, clear, and exact specification.

Reference is to be had to the accompanying drawing, forming a part of this specification, 10 in which the figure is a perspective view of my newly-designed corset.

The front strips, *a a*, side strips, *b b*, and back strips, *c*, are common. Between the strips *a b* appears on each side a strip, *d*, with diagonal end edges, *d' d'*, and with diagonal transverse ribs *d''*. Between the strips *b c* on each side appear the triangular gores *f g* and also 15 the side strips, *h*, which separate the triangular gores *f g*. The gores *f g* terminate at the waist in sharp points *i i*, and across them appear the transverse diagonal ribs *f'*. The ad-

jacent edges of the gores *f g* are parallel with each other, while the opposite edges diverge from each other, as shown clearly in the drawing.

25

I claim—

The design for a corset herein shown and described, the same consisting of parallel front strips, *a*, side strips, *b*, intermediate strips, *d*, having parallel diagonal upper and lower edges, 30 *d d'*, of equal length, showing diagonal ribs joining the adjacent edges of the strips *a b*, strips *h*, spaced from the strips *b*, the triangles *f*, intermediate to the strips *b h*, showing ribs joining the adjacent edges of the strips *b h*, 35 and the triangles *g*, showing ribs joining the adjacent edges of the strips *h*, with the back strips *c*.

EDWARD S. ROSENBLUTH.
